Primary Examiner — Mitchell Siegel*(74) Attorney, Agent, or Firm* — Stoel Rives LLP**CLAIM**

The ornamental design for a water slide, as shown and described.

DESCRIPTION

FIG. 1 is a top right isometric view of a water slide showing the new design;

FIG. 2 is a front side elevation view thereof;

FIG. 3 is a rear side elevation view thereof;

FIG. 4 is a right side elevation view thereof;

FIG. 5 is a left side elevation view thereof;

FIG. 6 is a top plan view thereof;

FIG. 7 is a bottom plan view thereof;

FIG. 8 is a top right isometric view of a second embodiment of the water slide;

FIG. 9 is a front side elevation view of thereof;

FIG. 10 is a rear side elevation view of thereof;

FIG. 11 is a right side elevation view of thereof;

FIG. 12 is a left side elevation view of thereof;

FIG. 13 is a top plan view of thereof; and,

FIG. 14 is a bottom plan view of thereof.

The broken line showing of base and steps is included for the purpose of illustrating and forms no part of the claimed design. The dotted lines are illustrating the water spray patterns.
